UNITED STATES PATENT OFFICE.

JACOB RICK, OF JERSEY CITY, NEW JERSEY, ASSIGNOR TO TRIUNE ENGINEERING CO., OF NEWARK, NEW JERSEY, A COPARTNERSHIP COMPOSED OF EDWARD B. PALMER, DOW B. HALLENECK, AND CHARLES G. LINKER, ALL OF NEWARK, NEW JERSEY, AND SAID JACOB RICK, OF JERSEY CITY, NEW JERSEY.

SPARK-PLUG.

1,159,994.

Specification of Letters Patent.

Patented Nov. 9, 1915.

Application filed March 11, 1915. Serial No. 13,662.

To all whom it may concern:

Be it known that I, JACOB RICK, a citizen of the United States, and a resident of Jersey City, in the county of Hudson and State 5 of New Jersey, have invented a new and Improved Spark-Plug, of which the following is a full, clear, and exact description.

This invention relates to spark plugs, particularly to an improved plug which is designed to eliminate any short circuiting by reason of the building up of carbon at the 10 sparking point.

Another object in view is to provide a spark plug with a contact ball and a cup-shaped runway, whereby the ball will provide a path for the passage of current and will obviate any corners or projections where carbon may accumulate.

A still further object of the invention is 15 to provide a spark plug with the lower or inner end arranged with a concaved or cup-shaped structure, whereby oil and other objectionable matter cannot reach the sparking members.

20 In the accompanying drawings: Figure 1 is a side view of a spark plug embodying the invention, certain parts being broken away for better illustrating the construction; Fig. 2 is a bottom plan view of the 25 structure shown in Fig. 1; Fig. 3 is a view similar to Fig. 1 but showing a slightly modified form of the invention; Fig. 4 is a bottom plan view of the structure shown in Fig. 3.

30 Referring to the accompanying drawings by numerals, 1 indicates a sleeve threaded at 2 so as to be rigidly screwed into place in the usual manner of spark plugs. The sleeve 1 is provided with a squared enlargement 3 for receiving a wrench, said enlargement being provided with a lip 4 adapted to be 35 pressed over in position for clamping the packing 5 tightly against the enlargement 6 of the porcelain stick 7. The porcelain stick 40 7 is supplied with a rod 8 having a head 9 rounded on its lower surface, and a threaded portion at the upper end for receiving a clamping nut 10 and a wire clamping nut 11. The lower end of the sleeve 1 is 45 provided with a shoulder 12 against which the lower end of the porcelain stick 7 is pressed when the lip 4 is forced into position, where-

by the porcelain stick is rigidly held against movement.

The lower end of porcelain stick 7 is provided with an annular groove 13, said groove being semicircular in cross section and merging into the periphery of the head 9 and also into the curved wall 14 of the ball race 15 provided in the lower end of sleeve 1. 55 By this construction and arrangement a ball 16 is maintained continually at the same distance from the head 9 when the ball is engaging the wall 14. It will of course be evident that if the ball 16 is in contact with 60 head 9 the spark will jump from the ball to the wall 14, but if the ball is engaging wall 14, as shown in Fig. 1, the spark will jump from the head 9 to ball 16. The ball race 15 is in free communication with the cylinder 65 70 of the engine to which the plug is attached through any desirable number of slots or openings 17.

It will also be observed that the extreme bottom end of the plug is provided with a 75 cup-shaped structure 18, whereby oil or any foreign matter will be directed away from ball 16 and associated parts. This, also, will reduce the chance of building up carbon at the terminal. By arranging the ball 16 so 80 as to be continuously the same distance from the head 9, and by providing all of the ball race 15 including groove 13 in a rounded shape, no corners or projections are provided to which carbon may adhere. The 85 ball 16 may be of any desired material, as for instance, steel, carbon or a mixture of metals, such as what is known as "meteor" metal.

Figs. 3 and 4 disclose a slightly modified 90 form of the invention in which a packing nut or sleeve 19 is used instead of the form of lip 4. Also the lower end of the sleeve 1' is provided with a tapering wall 20 which assists in directing any oil or undesirable 95 matter from the contact ball. In this form of the invention the cupped end 18' is deeper than that shown in Fig. 1, but it will be evident that in either form of the invention the concaved or cup-shaped structure may be 100 varied to any desired extent without departing from the spirit of the invention. It will also be noted that the runway 15 is cup-shaped and merges into the groove 13,

whereby a smooth continuous wall is presented to the ball 16 regardless of where the ball may be positioned. During the use of the plug it is evident that the spark may occur when the ball is half way between the head 9 and wall 14 which would naturally produce two sparks.

What I claim is:—

1. In a spark plug of the character described, a sleeve provided with an interior cup-shaped runway, an insulating stick arranged in said sleeve provided with a groove semicircular in cross section and merging in said runway, a ball arranged in said runway, and a contact member extending through said insulating stick provided with a rounded head, the periphery of said head merging into said groove.
2. In a spark plug of the character described, a sleeve provided with a runway semicircular in cross section, a porcelain stick arranged in said sleeve provided with a groove semicircular in cross section merging into said runway, a contact member carried by said porcelain stick and extending into said runway, and a contact ball arranged in said runway, said contact ball being a predetermined size less than the distance between the wall of said runway and the contact member carried by the porcelain stick.
3. In a spark plug of the character described, a sleeve provided with a runway at

the lower end, said lower end being provided also with a plurality of slots for affording communication between the runway and the exterior of the plug, a porcelain carried by said sleeve, a contact ball arranged in said runway, and a contact member carried by said porcelain, the lower end of said plug being concave and providing a structure which will guide oils and other objectionable matter away from said contact ball.

4. In a spark plug of the character described, a sleeve, a porcelain arranged in said sleeve, means for clamping the porcelain rigidly in position in said sleeve, said spark plug being formed with a cup-shaped runway, a plurality of openings extending from said runway to the exterior of the plug, with tapering exterior walls at the lower end and a concaved lower bottom, said tapering walls and said concaved bottom directing the oil away from said runway, a contact ball arranged in said runway, and a contact member connected with said porcelain.

In testimony whereof I have signed my name to this specification in the presence of two subscribing witnesses.

JACOB RICK.
